UNITED STATES PATENT OFFICE.

WILLIAM H. DE BUSK, OF CHICAGO, ILLINOIS, ASSIGNOR TO THE P & M COMPANY, OF CHICAGO, ILLINOIS, A CORPORATION OF ILLINOIS.

RAIL ANCHOR.

Application filed September 23, 1925. Serial No. 58,055.

My invention relates to rail anchors of the type adapted by engagement with a cross tie or other fixed portion of a railway track to hold a rail from moving longitudinally, and it is the principal object of my invention to provide a new and improved form and arrangement of parts by which this holding of the rail may be effected by the use of a construction of maximum simplicity which shall be easy to produce and to apply to the rail, and which shall be made up of a minimum amount of high grade steel for effecting the desired grip on the rail with a correspondingly large amount of lower grade steel for providing the desired extended bearing on the tie and for holding the device in operative position.

It is one of the specific objects of my invention to provide an improved form of extended bearing for transmitting the creeping pressure of the rail from the gripping element of the anchor to a cross tie, comprising improved means for holding the bearing in fixed position with respect to the gripping element. It is another object of my invention to improve devices of this type in sundry details hereinafter pointed out.

The preferred means by which I have accomplished my several objects are illustrated in the accompanying drawing and are hereinafter specifically described. That which I believe to be new and desire to cover by this application is set forth in the claims.

In the drawing:

Fig. 1 is a face view of my improved anchor in position upon a rail which is shown in cross section, partly broken away.

Fig. 2 is a face view of one end portion of the blank from which the retainer member of my improved anchor is formed.

Fig. 3 is a top plan view of the parts shown in Fig. 1, with the upper end portion of the clip broken away for clearness of illustration; and

Fig. 4 is a vertical sectional view taken on line 4-4 of Fig. 1.

Referring to the several figures of the drawing, 10 indicates a rail supported by a cross tie 11. A clip 12 is shown in position upon the flange at the right in Fig. 1, such clip being formed from a heavy bar of high grade steel bent into shape, the size and shape of the clip being such normally,

as indicated by dotted lines in Fig. 1, that the end portions or jaws of the clip are spread apart by the operation of driving the clip into position upon the flange. The bar from which the clip 12 is made is preferably of such size as to have a very strong grip upon the flange of the rail so as to resist very strongly longitudinal movement of the rail 10 with respect to the clip.

The clip 12 is held in position by means of a retainer in the form of a heavy sheet metal plate 13 of lower grade metal than that of the clip 12. The plate 13 is secured in vertically disposed edgewise position between the clip 12 and the cross tie 11, serving as a bearing means for transmitting the creeping pressure of the rail from the clip 12 to the cross tie. The plate 13 is secured to the clip 12 by means of a tongue or arm 14 formed integrally with the plate at its upper edge portion and bent over so as to have snug engagement with the lower arm of the clip, as is best shown in Fig. 4. The plate 13 is reinforced and strengthened by means of flanges 15 and 16 formed integrally therewith and turned at right angles with respect to the body of the plate. As is clearly shown in Figs. 1 and 3, the flange 16 stands in engagement with the outer face of the clip 12.

At its inner end, the plate 13 is provided with a transversely extending arm 17, which is provided with a shoulder 18 adapted to stand in engagement with the side face of the flange at that side of the rail, as is best shown in Fig. 1. Formed integrally with the arm 17, and bent at an angle with respect to such arm, there is a tongue 19, the inner end portion of which is provided with a shoulder 20 and a diagonally disposed bottom face 21.

In the application of the anchor to a rail, the clip 12 is first slipped into engagement with the arm 14 in substantially the relationship as shown in Fig. 1; the clip 12 is then inserted over the flange at the right in Fig. 1, and the clip 12 and the retainer are both driven toward the left in said Fig. 1, preferably by blows of a hammer or maul upon the outer face of the flange 16. When the clip 12 has reached its operative position at the limit of its movement toward the left in Fig. 1, the arm 17 will have attained a position directly transverse with respect to the rail and in close proximity to the cross tie 11.

11. The tongue 19, however, will at this point in the application of the anchor be standing underneath the flange at the left of the rail. The tongue 19 is then to be bent outwardly through the use of any suitable tool so as to clear the edge of the rail, whereupon the arm 17 is to be forced upwardly for permitting the tongue 19 to snap past the edge of the flange into the position as shown in Figs. 1 and 3 bringing the diagonally disposed bottom face 21 of the tongue into engagement with the diagonally disposed upper face of the flange, and bringing the shoulder 20 into engagement with the side face of the flange. In this position, the retainer serves to hold the clip 12 against movement transversely of the rail out of engagement with the rail, both the flange 16 and the arm 14 serving to prevent movement of the clip 12 toward the right in Fig. 1 with respect to the retainer. Furthermore, the engagement of the arm 16 with the outer face of the clip 12 at one side of the rail and the engagement of the shoulders 18 and 20 with the opposite edge of the rail base have a tendency to increase the grip of the anchor on the rail under certain conditions when the rail is moved longitudinally. The increased gripping action effected by reason of the engagement of shoulder 18 with the edge of the rail base is produced in the event that the tie against which the anchor bears extends diagonally across the track so that the clip end of the anchor bears against the tie and the shoulder end 18 of the anchor stands away from the tie. Under such condition the retaining member may be moved by the creeping movement of the rail to a diagonal position across the rail. The increased grip resulting from the angular position of the tongue and the engagement of the shoulder 20 with the edge of the rail is effected when the creeping movement of the rail forces the shoulder end of the retaining member against the tie. This force tends to move the tongue 19 toward the arm 14 of the retaining member, thereby exerting a force tending to move the retaining member in the direction of its length transversely of the rail.

By my construction I have provided a very simple and very efficient means for holding the clip 12 in operative position on the flange, while at the same time providing a very effective and very strong extended bearing for transmitting the creeping pressure of the rail from the clip to the cross tie 11. Inasmuch as the retainer 13 is of comparatively low grade material, it can be produced very cheaply and very readily by a stamping operation, the clip 12 which is formed of high grade metal being relied upon for gripping the rail.

While I prefer to employ the construction substantially as shown in my drawing,

it will be understood that I do not desire to be limited to that form except as the same is hereinafter specifically claimed, inasmuch as it is evident that changes may well be made in the particular form of construction 70 without departing from the spirit of my invention.

I claim:

1. In a rail anchor, the combination of a clip adapted to be driven into gripping engagement with the flange at one side of a rail, and a retainer in the form of a plate interposed in vertically edgewise position between the clip and the cross tie for holding the clip in operative position on the rail, 75 said retainer comprising a hook engaging the lower arm of the clip and a second hook engaging the top face of the flange at the opposite side for holding the retainer in operative raised position and preventing the 80 clip from backing transversely from the rail.

2. In a rail anchor, the combination of a clip adapted to be driven into gripping engagement with the flange at one side of a 90 rail, and a retainer for holding the clip in operative position on the rail, comprising a hook slipped from above into engagement with the lower arm of the clip and a second hook engaging about the edge of the flange 95 at the opposite side of the rail.

3. In a rail anchor, the combination of a clip adapted to be driven into gripping engagement with the flange at one side of a rail, and a retainer for holding the clip in 100 operative position on a rail, comprising a hook engaging the lower arm of the clip from above between the rail and said arm, and a second hook at the opposite end of the retainer engaging the opposite side of the 105 rail.

4. In a rail anchor, the combination of a clip adapted to be driven into gripping engagement with the flange at one side of a rail, and a retainer for holding the clip in 110 operative position on the rail and serving as an extended bearing for transmitting the creeping pressure of the rail from the clip to the cross tie, said retainer comprising a hook adapted by engagement with the lower arm of the clip to hold the retainer from turning about a horizontal axis extending transversely of the rail, and a second hook engaging the opposite side of the rail.

5. In a rail anchor, the combination of a 120 clip adapted to be driven into gripping engagement with the flange at one side of a rail, and a retainer in the form of a plate interposed in vertically edgewise position between the clip and the cross tie for holding the clip in operative position on a rail and serving as an extended bearing for transmitting the creeping pressure of the rail from the clip to the cross tie, said retainer comprising a hook in the form of a tongue 125

bent downwardly opposite the face of the plate for engaging the lower arm of the clip and holding the plate from turning with respect thereto, and a second hook engaging 5 the opposite side of the rail.

6. In a rail anchor, the combination of a clip adapted to be driven into gripping engagement with the flange at one side of a rail, and a retainer in the form of a plate 10 interposed in vertically edgewise position between the clip and the cross tie for holding the clip in operative position on the rail, said retainer comprising means adapted by contact with the outwardly disposed face portion 15 of the clip to hold the clip from backing transversely from the flange, a shoulder at the opposite end portion of the retainer in position to engage the outer face of the flange at that side of the rail, and means adjacent to said shoulder for holding that end 20 of the retainer in operative raised position on the rail.

7. In a rail anchor, the combination of a clip adapted to be driven into gripping engagement with the flange at one side of a rail, and a retainer in the form of a plate 25 interposed in vertically edgewise position between the clip and the cross tie for holding the clip in operative position on the rail, said retainer comprising a flange at one end engaging the outside face of the clip, a shoulder at the opposite end portion of the retainer in position to engage the outer face of the flange at that side of the rail, and means adjacent to said shoulder for holding that end 30 of the retainer in operative raised position on the rail.

8. In a rail anchor, the combination of a clip adapted to be driven into gripping engagement with the flange at one side of a rail, and a retainer in the form of a plate 35 interposed in vertically edgewise position between the clip and the cross tie for holding the clip in operative position on the rail, said retainer comprising a hook at one end adapted by engagement with said clip to hold the clip in fixed position relative to the retainer, a shoulder at the opposite end portion of the retainer in position to engage the outer face of the flange at that 40 side of the rail, and means adjacent to said shoulder for holding that end of the retainer in operative raised position on the rail.

9. In a rail anchor, the combination of a clip adapted to be driven into gripping engagement with the flange at one side of a rail, a retainer in the form of a plate interposed in vertically edgewise position between the clip and the cross tie for holding the clip 45 in operative position on the rail, said retainer comprising means adapted by contact with the outwardly disposed face portion of the clip to hold the clip from backing transversely from the flange, a shoulder at the opposite end portion of the retainer in position 50

to engage the outer face of the flange at that side of the rail, and an arm formed on the retainer adjacent to said shoulder adapted by snap engagement with the flange at that side of the rail to hold the shoulder 70 in operative raised position engaging the edge of the flange.

10. In a rail anchor, the combination of a clip adapted to be driven into gripping engagement with the flange at one side of a rail, and a retainer in the form of a plate 75 interposed in vertically edgewise position between the clip and the cross tie for holding the clip in operative position on the rail, said retainer comprising means adapted by contact with the outwardly disposed face portion of the clip to hold the clip from backing transversely from the flange, a shoulder at the opposite end portion of the retainer in position to engage the outer face of the flange 80 at that side of the rail, and an arm formed on the retainer adjacent to said shoulder and bent to extend in the direction away from the cross tie adapted to be sprung outwardly to pass the edge of the flange and adapted by engagement with the top face of the flange to hold the shoulder in operative engagement 85 with the flange.

11. In a rail anchor, the combination of a clip adapted to be driven into gripping engagement with the flange at one side of a rail, and a retainer in the form of a plate 90 interposed in vertically edgewise position between the clip and the cross tie for holding the clip in operative position on the rail, said retainer comprising means adapted by contact with the outwardly disposed face portion of the clip to hold the clip from backing transversely from the flange, and an arm formed on the retainer at its other 95 end adapted to engage both the side edge face and the top face of the flange at that side of the rail for holding the retainer in operative position on the rail.

12. In a rail anchor, the combination of a clip adapted to be driven into gripping engagement with the flange at one side of a rail, and a retainer in the form of a plate 100 interposed in vertically edgewise position between the clip and the cross tie for holding the clip in operative position on the rail, said retainer comprising means adapted by contact with the outwardly disposed face portion of the clip to hold the clip from backing transversely from the flange, and an arm formed on the retainer at its other 105 end adapted by snap engagement with the top face of the flange at that side of the rail to hold the retainer in operative gripping relationship with the rail, said arm being 110 provided with a shoulder adapted to engage the side face of the flange.

13. In a rail anchor, the combination of a clip adapted to be driven into gripping engagement with the flange at one side of a 115

5 rail, and a plate interposed in vertically edgewise position between the clip and the cross tie and held in position for providing an extended bearing for transmitting the 10 creeping pressure of the rail from the clip to the cross tie by means of a hook embracing the lower arm of the clip.

14. In a rail anchor, the combination of a clip adapted to be driven into gripping engagement with the flange at one side of a rail, and a plate interposed in vertically edgewise position between the clip and the cross tie and held in position for providing an extended bearing for transmitting the 15 creeping pressure of the rail from the clip to the cross tie by means of a hook formed integrally on the upper edge of the plate and embracing the lower arm of the clip.

15. In a rail anchor, the combination of a clip adapted to be driven into gripping engagement with the flange at one side of a rail, a plate interposed in vertically edgewise position between the clip and the cross tie and held in position for providing an 20 extended bearing for transmitting the creeping pressure of the rail from the clip to the cross tie by means of a hook embracing the lower arm of the clip, and flanges formed on opposite ends of the bearing portion 25 of said plate and extending longitudinally of the rail for strengthening the plate.

16. In a rail anchor, the combination of a clip adapted to be driven into gripping engagement with the flange at one side of a rail, a plate interposed in vertically edgewise position between the clip and the cross tie and held in position for providing an extended bearing for transmitting the creeping 30 pressure of the rail from the clip to the cross tie by means of a hook embracing the lower arm of the clip, and flanges formed on opposite ends of the bearing portion of said plate and extending longitudinally of the rail for strengthening the plate, the flange at one end engaging the outer face 35 of the clip.

17. In a rail anchor, the combination of a clip adapted to be driven into gripping engagement with the flange at one side of a rail, a plate interposed in vertically edgewise position between the clip and the cross tie and held in position for providing an extended bearing for transmitting the creeping pressure of the rail from the clip to the cross tie by means of a hook embracing the lower arm of the clip, and means for holding the clip and plate from backing transversely from the flange of the rail.

18. In a rail anchor, the combination of a clip adapted to be driven into gripping engagement with the flange at one side of a rail, a plate interposed in vertically edgewise position between the clip and the cross tie and held in position for providing an 65 extended bearing for transmitting the creeping

70 ing pressure of the rail from the clip to the cross tie by means of a hook embracing the lower arm of the clip, and means formed integrally with the plate adapted by engagement with the opposite side of the rail to hold the clip from backing transversely from the flange of the rail.

19. In a rail anchor, the combination of a clip adapted to be driven into gripping engagement with the flange at one side of a rail, a plate interposed in vertically edgewise position between the clip and the cross tie and held in position for providing an extended bearing for transmitting the creeping pressure of the rail from the clip to the cross tie by means of a hook embracing the lower arm of the clip, flanges formed on opposite ends of the bearing portion of the plate and extending longitudinally of the rail for strengthening the plates, and means 85 acting through the medium of the plate for holding the clip from backing transversely from the flange.

20. In a rail anchor, the combination of a clip adapted to be driven into gripping engagement with a rail base flange at one side of the rail, and a retaining member adapted to bear against a cross tie and comprising a plate disposed to engage one side of the clip and provided at one end with 90 means for engaging the outer end face of said clip, and at the other end with a hook disposed at an angle to the plate, normally extending in a direction away from the adjacent cross tie, and adapted to engage the 95 edge of the rail base at the opposite side of the rail.

21. In a rail anchor, the combination of a clip adapted to be driven into gripping engagement with a rail base flange at one 100 side of a rail, and a retaining member comprising a plate disposed to engage one side of the clip and provided at one end with means for engaging said clip to prevent outward movement thereof and provided at the other end with means for engaging the edge 105 of the rail base at the opposite side of the rail, whereby an increased grip of the anchor is effected during the presence of creeping movement of the rail.

22. A rail anchor comprising means provided for bearing against the cross tie and means for engaging opposite edges of the rail base, the means for engaging one edge of said base comprising an angularly disposed tongue adapted to be moved by the creeping movement of the rail toward the first mentioned means, whereby the force exerted on said tongue by said creeping movement of the rail tends to move the anchor transversely of the rail to increase its grip on the rail base.

23. A rail anchor comprising means provided for bearing against a cross tie at opposite sides of the rail and means for engag-

ing opposite edges of the rail base, the means for engaging one edge of said base comprising an angularly disposed tongue adapted to be moved by the creeping movement of the rail toward a position perpendicular to the length of the rail, whereby said creeping movement tends to move the anchor transversely of the rail to increase its grip on the rail base.

24. A rail anchor comprising means provided for bearing against a cross tie at opposite sides of the rail and means for engaging opposite edges of the rail base, the means for engaging one edge of said base comprising an angularly disposed tongue formed with a shoulder for engaging the edge of the rail base flange so that the arm is adapted to be moved by the creeping movement of the rail toward a position perpendicular to the length of the rail, whereby said creeping movement tends to move the anchor transversely of the rail to increase its grip on the rail base.

25. A rail anchor comprising means for gripping the base flange of a railroad rail at one side thereof, a bar extending across beneath the rail base, provided with a tongue for engaging the other edge of the rail base and adapted to bear against a cross tie to

prevent movement of the bar longitudinally of a rail in a direction toward the tie, the said tongue being disposed at an angle to said bar and extending away from the adjacent cross tie whereby the pressure of the anchor against the tie and tendency which the creeping movement of the rail has to move the tongue toward a tie exerts a force transversely of the rail to increase the grip of the anchor on the rail base.

26. In a rail anchor, the combination of a clip adapted to be driven into gripping engagement with a rail base flange at one side of the rail, and a retaining member comprising a plate disposed to engage one side of the clip, arranged to bear against a vertical face of the cross-tie provided at one end with means for engaging the outer face of said clip, and at the other end with a resilient tongue disposed at an angle to the plate, normally extending away from the adjacent cross tie and provided with a shoulder adapted to bear against the vertical face of the rail base, whereby creeping movement of the rail tends to move the tongue toward the adjacent cross tie, thereby exerting a force transversely of the rail base to increase the grip of the anchor on the rail.
